UNITED STATES PATENT OFFICE.

ROBERT E. MCFARLANE, OF DULUTH, MINNESOTA.

TOURNIQUET.

1,302,062.

Specification of Letters Patent. Patented Apr. 29, 1919.

Application filed August 6, 1918. Serial No. 248,536.

To all whom it may concern:

Be it known that I, ROBERT E. MCFARLANE, a citizen of the United States, residing at Duluth, in the county of St. Louis 5 and State of Minnesota, have invented certain new and useful Improvements in Tourniquets, of which the following is a specification, reference being had therein to the accompanying drawing.

10 My invention relates to surgical instruments and more particularly to an improved form of tourniquet.

An object of my invention is to provide an instrument of the above type which may 15 be easily and very quickly adjusted to a limb to be treated.

A further object of the invention is to provide an arrangement whereby additional pressure may be accurately applied to a particular spot on the limb such as over an artery.

Various other objects of my invention will be apparent from a perusal of the following specification and the accompanying drawings.

25 My invention is illustrated in the accompanying drawings in which—

Figure 1 is a sectional view of my device complete.

30 Fig. 2 is a transverse section through the handle taken on the line 2—2 of Fig. 1 with the band lock in its raised position.

Fig. 3 is a top plan view of the handle by itself.

35 Referring to the drawings in detail, the handle 1, formed of suitable light and strong material such as aluminum, is provided with a chamber 2 having end openings 3 and 4 and a top opening 5. A strap or band 6 of suitable flexible material such as leather has one end 7 secured to the handle within the recess by means of a head formed on its end and held within the chamber 2 between the lower wall thereof and a transverse bar

40 8. The head at the end 7 may be formed by bending the end of the strap over and stitching or riveting through as indicated. The end of the band may be fixed within the handle in any well known manner. The

45 50 method shown, however, is preferred, as it enables the band to be removed and replaced by simply raising band lock 10 perpendicular and threading the band into chamber 2 through top opening 5 and pulling the free

55 end out through the opening 3 until the headed end 7 wedges in between the lower

wall of the chamber and the transverse bar 8. From the fixed end 7 the band 6 extends out and back through the opening 3 forming a loop as shown, the free end 9 of the 60 band passing through the band lock 10 within the chamber 2 and out through the opening 4. The band lock 10 is preferably in the form of a cinch lock pivoted within the chamber by means of pivot lugs 12 journaled 65 in sockets 13 formed in opposite side walls of the chamber, and provided with a slot or opening 14 through which the band passes. The lock 10 is arranged in the chamber 2 below the opening 5 to permit an operator to 70 manipulate it through the opening 5 with the thumb or finger. The handle 1 at the forward portion or loop end is provided with a downwardly projecting portion 15 arranged to engage with and exert a down- 75 ward pressure on the band at 16 when the handle is swung downwardly toward the loop in the position shown in Fig. 1, the point where the ends of the loop enter the opening 3 acting as a fulcrum. The surface 80 15 is preferably formed with a broad curvature as shown to avoid an undue concentration of the pressure. To hold the lever in different positions of adjustment I provide a handle lock preferably in the form as shown 85 which consists of a spring hook or snap 17 carried at the free end of the handle 1 and adapted to engage any one of a series of rings 18 fastened to the band 6.

In operation the loop of the band 6 is 90 placed over the limb to be treated and the free end 9 of the band pulled through the handle in the direction indicated by the arrow in Fig. 1, while holding the handle up or more or less in a radius of the loop, until 95 the required compression is obtained, whereupon the thumb or finger is inserted through the opening 5 and the lock 10 pressed downwardly so as to take a cinch hold on the band and prevent its slipping back through the 100 opening 3. The lever 1 is then swung downwardly toward the position shown in Fig. 1 to exert an additional pressure at the point 16, the loop being originally positioned to bring this point over a particular portion of 105 the limb where additional pressure is desirable, the handle being then locked in position by engaging the hook 17 with whichever one of the rings 18 is required to hold the handle in adjusted position. From the 110 above description it will be seen that my device may very easily and quickly be applied

to the limb to be treated and the additional pressure accurately adjusted and applied to the selected portion of the limb, and readily locked in adjustment or released as required.

5 While I have here shown and described a specific embodiment of my invention, for purposes of disclosure, it is to be understood that the invention is not limited to such specific embodiment but that all such modifications and variants thereof as fairly fall within the scope of the appended claims are contemplated by me.

10 Having thus described my invention what I claim and desire to secure by Letters Patent is—

15 1. A tourniquet comprising a flexible band formed in a loop, means arranged to bear against the outer surface of the loop and exert an inward pressure thereon at a given point, and means for locking said pressure applying means in different adjustments.

20 2. A tourniquet comprising a band or loop arranged to embrace a limb to be compressed, means for tightening the loop, and

25 3. A lever fulcrumed at the ends of the loop and provided with a compression portion intermediate the loop ends and the free end of the lever.

30 4. A tourniquet comprising a band or loop arranged to embrace a limb to be compressed, means for tightening the loop, and a lever fulcrumed on the loop and provided with a compression portion intermediate the fulcrum and the free end of the lever, to-

35 5. together with means for holding the free end of said lever in different positions in relation to the loop to maintain different degrees of pressure on the limb beneath the said compression portion of the lever.

4. A tourniquet comprising a lever handle, an adjustable band or loop of flexible material carried at one end of said handle, and means for holding the free end of the handle at a given distance from the loop to cause a portion of the handle intermediate the ends to press inwardly against the loop.

5. A tourniquet comprising a flexible loop or band arranged to surround a limb to be treated, and a lever handle fulcrumed on the loop and having a compressing member projecting out of line with the fulcrum and the free end of the handle in the plane of the loop.

6. A tourniquet comprising a flexible loop or band arranged to surround a limb to be treated, means for adjusting the size of the loop, a handle having one end connected to said loop and arranged to cause a portion between the connected end and the free end to press inwardly against the loop when the free end is swung toward the loop, and adjustable holding means between the free end of the handle and the loop.

7. A tourniquet comprising an elongated handle, a strap or band having one end fixed within the handle and a free end passing out of the handle at one end and back through the same end and through a portion of the length of the handle to form a closed loop, a band lock situated within the handle for locking the free end of the band passing through the handle, a projecting portion on the handle intermediate the ends, and a handle lock for locking the end of the handle opposite the loop end to different portions of the looped portion of the band.

In testimony whereof I affix my signature.

ROBERT E. McFARLANE.
